UNITED STATES PATENT OFFICE.

GUY C. PRICKETT, OF CINCINNATI, OHIO.

DESIGN FOR A MEMBER FOR PAIRS OF PLIERS.

SPECIFICATION forming part of Design No. 31,085, dated June 27, 1899.

Application filed May 10, 1899. Serial No. 718,290. Term of patent 14 years.

To all whom it may concern:

Be it known that I, GUY C. PRICKETT, a citizen of the United States, residing at Cincinnati, in the county of Hamilton and State of Ohio, have invented and produced a new and original Design for a Member for Pairs of Pliers; and I do hereby declare the following to be a full, clear, and exact description of the same, reference being had to the accompanying drawing, which forms a part of this specification.

The leading feature of my design relates to the peculiar configuration of the nose of the plier member, the configuration consisting in a bent nose terminating with a flat extension.

The accompanying drawing is a side elevation of a plier member embodying my novel design.

The handle A has a bent nose a, terminating with a flat extension a'.

I claim as my invention—

The design for a member of a pair of pliers, as herein shown and described.

In testimony whereof I affix my signature in presence of two witnesses.

GUY C. PRICKETT.

Witnesses:

JAMES H. LAYMAN,
JESSE M. SIMON.
